CLOSURE FOR RECEPTACLES

Percy M. Thorn, New Rochelle, N. Y.

Application April 6, 1936, Serial No. 72,950

7 Claims. (Cl. 221—62)

This invention relates to closures and more particularly to closures for paper containers.

It is an object of this invention to provide a closure which may be readily opened and closed at will and which will be so inexpensive to manufacture that it will be available for the most inexpensive type of packages.

It is a further object to provide a closure which will be so flat that when applied to containers it will permit them to be stacked one upon the other without danger of falling.

Containers are of two general types; one class, made of glass, hard paper, or tin, or other metal, and carrying the more expensive material, has ordinarily been provided with some type of closure which could at will be opened and closed to give a tight joint; the other type of containers, ordinarily made of paper of one type or another, as for example the less expensive cardboards have not been deemed suitable for closures which can be opened and closed other than some cover which can be taken on and off, and such closure elements as have been suggested have not been satisfactory.

It is a further object of this invention to provide a closure which can satisfactorily be used, particularly upon the latter type of containers.

It is a further object of the invention to provide a container that may be made in quantity production and to this end it is an object to provide a closure which can be made and assembled as a unit when desired, and which can be applied as a unit to containers of standard construction.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description, taken in connection with the accompanying drawings, in which:

Figure 1 is a top plan view of a container embodying this invention with the face member in part removed to show the interior construction.

Figure 2 is a section along the line 2—2 of Figure 1.

Figure 3 is a plan view of a modified form of the invention.

Figure 4 is a section on the line 4—4 of Figure 3.

Figure 5 is a view partly in section showing another modification.

Figure 6 is a section on the line 6—6 of Figure 5.

Figure 7 is a sectional view of a further modification.

Figure 8 is a side elevation and Figure 9 is a section of a closure of this invention applied to the side wall of a container.

Since one of the primary purposes of the invention is to provide a closure which may be made of paper, I have chosen to illustrate as made of that material. It will be understood, however, that certain features of the container may be of more general application.

In the drawings the numeral 10 designates a container such as the box in which breakfast cereals are ordinarily sold and showing a closure of this invention carried upon one end wall 11 thereof. The closure comprises primarily an outer face 12 held parallel to and spaced from the end wall 11 to provide a recess 13 for a shutter 14. As illustrated, the outer face 12 is of generally circular form and has attached to its periphery on its under side an annular rim 15, the thickness of which serves to provide the recess 13 for the shutter.

The shutter 14 is pivoted to one of the stationary members for swinging movement. I have chosen to illustrate it as pivoted to the end face 12 at 16, in order that when the elements are assembled, the different parts of the closure will be held together as a unit independent of the container. The pivot 16 is arranged near the periphery of the recess 13 and the shutter may be of elongated shape defined by circular arcs so that it may swing from one side of the recess 13 to the other about the pivot 16. On the other side of the shutter from the pivot at the point 17, there is attached to it a cord 18 and grooves 19 are cut in the annular rim 15, at appropriate points so that the cord may pass through them to the exterior. In this manner it will be clear that by pulling upon one side 20 of the cord, the shutter may be moved to one side of its recess, and by pulling the other side 21, it may be moved to the other side of the recess.

When the shutter is in one position, as for example the downward position shown in Figure 1, aligned openings 22, 22a, and 22b are cut through the end wall 11, the shutter 14, and the outer face 12, so that with the shutter in this position, access is afforded to the contents of the box. As soon, however, as the cord 20 is pulled to bring this shutter to the upper or dotted

line position as in Figure 1, the opening 22a in the shutter moves out of alignment with the openings 22 and 22b in the end wall and the outer face member 12 to close the box.

5 The closure of the construction just described is assembled as a unit by gluing the rim 15 to the under face 12 of the closure, attaching the shutter member 14 by its pivot 16 and inserting the cord ends 20 and 21 through the recesses 19.

10 As will be seen, the edges of the grooves 19 are preferably rounded as at 19a so that the string will pull easily even if pulled at an angle.

Such a closure may be manufactured in quantity and attached to any container at will, by

15 pasting it upon the under face thereof. It will readily be understood that the opening 22 in the wall of the container may either be preformed in position to register with the openings in the closure when the latter is applied, or this opening

20 may be perforated to facilitate ready removal, or it may be left unformed until the package reaches the hands of the consumer, in which case the consumer may cut the opening 22 in the container with a sharp knife, thus for the first time

25 breaking the seal of the package. In either event, once the registering openings are provided, the shutter may be used to open and close the container at will.

In this embodiment there is also illustrated a 30 feature which, in some instances is a feature of some importance, namely that immediately surrounding the central opening there is impressed within the end wall 11 an annular rib 23 and the material of the end wall within the rib 23 is

35 slightly raised above the level of the rest of the end wall as shown at 24. By this construction the soft paper of the end wall is materially stiffened to prevent the end wall sagging away from the shutter and the portion of the end wall immediately surrounding the opening forms a tight joint against the shutter at all times. It will be understood that this feature may be employed with any of the embodiments herein illustrated whenever desired.

40 In the embodiment illustrated in Figures 3 and 4, the parts of the construction correspond generally to the construction illustrated in Figures 1 and 2, except that the outer face 12 is bent downwardly or offset to provide a terminal wall 115 for the recess 13, and a flat peripheral extension

45 115a for attachment to the end wall of the container. Where this construction is employed, the openings 119 are cut through the terminal wall 115 of the recess and in this manner the terminal wall 115 is utilized to limit the movement of the shutter and prevent a tendency of the shutter to slide out beneath the peripheral extension 115a.

To accomplish this end more particularly, if desired, the cord 18a may be attached to the 50 under face of the shutter at 17a so that as the shutter is moved to the limit of its travel in either direction, the cord passes from its under face up through the openings 119, and in this manner definitely prevents the shutter from sliding 55 underneath the under face at the point where it is glued to the container. In this figure also there is shown a different method of producing a tight closure between the shutter and the periphery of the opening comprising a paper or fibre washer 60 123 which may be attached to the end wall of the container around the opening 122.

In the form of the invention illustrated in Figures 5 and 6, the form is similar to that illustrated in Figures 3 and 4, except that a slot 219 is 65 cut in the terminal wall 215 to permit a tab 218

to extend outwardly of the under face, and this slot is of such a length that the shutter may be moved from its open to closed position by means of the tab 218. In this figure also there is applied to the under surface of the end wall 211 a coating of a material adapted to shrink during drying, such for example as gelatine or starch glues, which by reason of its stiffness will strengthen the sheet and by reason of its shrinkage will bow the wall 211 upwardly toward the 10 shutter.

15 In the form of the invention disclosed in Figure 7, the recess 313 for the shutter is formed by bending the outer face 312 downwardly to form a terminal wall 315 and underneath to form an under wall 316. Similarly on the other side of the closure, the material of the face is bent downwardly to form a terminal wall 315 and underneath to form an under wall 316a. The under walls 316 and 316a extend to a point of meeting 20 at 317 in order that the shutter itself may always effect a tight closure, but this meeting point 317 is preferably disposed completely at one side of the registering openings 322, 322a and 322b so that the under face 316a forms a tight closure 25 completely around the opening.

This embodiment may be operated either by a cord such as is illustrated in Figures 1 and 3, or by tabs as illustrated in Figure 5. The essential characteristic of this particular embodiment 30 comprises the fact that the continuous sheet is folded over to form the terminal walls of the recess so that there is no danger of the shutter sliding out of the recess to the side and becoming bound.

If it is desired to employ a reinforcing rim and raised central section such as were illustrated at 35 23 and 24 in Figures 1 and 2, in this embodiment of the invention or in any other embodiment in which an under sheet is inserted between the shutter and the end wall of the container, it will be understood that the rim and raised portion may be imparted to the interposed sheet such as the bent over portion 316a or to the end wall of the container, as desired.

The embodiment illustrated in Figures 8 and 9 45 is similar to the embodiment of Figure 1, except that in lieu of the form of pivot employed in Figure 1, the annular rim 415 is cut with a recess 416 into which there is projected a point 417 formed upon the shutter, and the opposite wall 418 of the recess 413 is cut upon an arc about the point 416 as a center so that as the cords 420 or 421 are pulled, the shutter is moved about the point 416 50 as a pivot and at all times retains its place within the recess.

In this figure there is shown another method of insuring a tight joint between the shutter and the wall of the container. In this form the circumferential rim may be of greater thickness at the 60 outer periphery than at the corner, as for example being made of two parts 415 and 415a, one of which, 415a, is of much larger internal diameter than the other so that when the closure is glued to the container the wall of the container will 65 bulge outwardly toward the shutter.

In any of the foregoing constructions it will be seen that the peripheral wall of the face member greatly strengthens the wall of the container at points closely adjacent to the opening 70 so that the closure may be employed on containers having relatively flexible walls and still maintain a sufficiently tight closure.

Since certain changes may be made in the above construction and different embodiments 75

of the invention could be made without departing from the scope thereof, it is intended that all matter contained in the above description or shown in the accompanying drawings shall 5 be interpreted as illustrative and not in a limiting sense.

It is also to be understood that the following 10 claims are intended to cover all of the generic and specific features of the invention herein described, and all statements of the scope of the invention which, as a matter of language, might be said to fall therebetween.

Having described my invention, what I claim as new and desire to secure by Letters Patent is:

15 1. A closure for containers or the like comprising a face member of paper, a circumferential rim around and fastened to the face member upon its under side and adapted to be attached to the end wall of a paper container and to form therewith a compartment, a shutter within said compartment and pivoted to said face member, means for attaching said rim to a container, there being aligned openings in said face member and said shutter in one position of the latter.

20 2. A closure for containers or the like comprising a face member, a circumferential rim around and fastened to the face member upon its under side and adapted to be attached to the end wall of a container and to form therewith a compartment, a shutter within said compartment and pivoted to said face member, means for attaching said rim to a container, there being aligned openings in said face member and said shutter in one position of the latter, there being a cord 35 attached to said shutter extending outwardly on both sides for operating the shutter.

25 3. A closure for containers adapted to be attached to a container comprising a pair of paper elements immovably fastened to each other and defining a compartment between them, a shutter pivoted at one end within said compartment and contacting both, a member attached to the free end of the shutter and passing to the ex-

terior for operating the shutter, there being aligned openings through said elements and said shutter in one position of the latter.

4. A closure for containers comprising a pair of paper elements immovably held in spaced relation, a shutter pivotally mounted between them, there being aligned openings in said elements and said shutter in one position of the latter, and means to stiffen one of said elements and to concentrate pressure between it and said shutter at the periphery of the opening in said element.

5. A closure for containers comprising a pair of paper elements held in spaced relation, a shutter pivotally mounted between them, there being 15 aligned openings in said elements and said shutter in one position of the latter, and means to bow one of said elements toward said shutter comprising a coating of adhesive on the opposite side of said element to concentrate pressure 20 between one of said elements and said shutter to the periphery of the opening in said element.

6. A closure for containers comprising a pair of paper elements held in spaced relation, a shutter pivotally mounted between them, there being 25 aligned openings in said elements and said shutter in one position of the latter, and means for holding said elements in spaced relation being so constructed and arranged as to bow said elements toward each other.

7. A closure for containers comprising a shutter movable over a wall of said container and there being aligned openings in said shutter and in the wall of the container, means upon the container wall and bearing upon the shutter at the 35 periphery of the opening and said means being adapted to stiffen the container wall adjacent to the opening, said means comprising a circumferential rib substantially at the periphery of the opening having an inner edge of the rib extending above the general plane of the end wall. 40

PERCY M. THORN.
